LIFT TRUCK

George Quayle, Philadelphia, Pa., assignor to The
Yale & Towne Manufacturing Company, Stamford, Conn., a corporation of Connecticut

Application January 29, 1944, Serial No. 520,185

21 Claims. (Cl. 254—2)

1

This invention relates to an industrial truck of the type in which an elevating platform is lifted relatively to a lifting head or main frame by lifting means actuated relatively to the lifting head. More particularly, my invention relates to a truck of the class described in which the lifting mechanism comprises mechanically actuated means carried in the lifting head and adapted to apply lifting effort to the elevating platform whereby to raise that platform relatively to the lifting head. In setting forth my invention I shall describe it as applied to an elevating truck of the single frame type; that is, a truck in which the elevating platform is mounted at its forward end relatively to the lifting head by means on the lifting head, while the rear end of the elevating platform is raised through load wheels pivotally supported at that rear end and actuated through suitable mechanism extending toward the lifting head. In my Patent No. 2,274,164 I illustrate a single frame truck of the class described.

The invention of this application resides particularly in a new type of lifting mechanism and means for controlling that lifting mechanism. One important feature of my invention resides in the utilization of a novel form of lifting member secured to the elevating platform and extending into position for operation by a lifting lever that is preferably the steering handle of the truck. As a further feature of this part of my invention, the lifting member is in the form of a strut that hangs downwardly from the elevating platform in substantially the steering axis of the truck for actuation by the steering and lifting handle. As still a further feature of this part of my invention, the strut is rotatable relatively to the elevating platform in the steering axis of the truck and is thereby adapted for cooperation with lifting means actuated by the steering and lifting handle in all steering positions.

A further feature of my invention resides in the use of compound lifting mechanism actuated by the steering and lifting handle, and cooperative with the lifting member or lifting strut. The arrangement of the parts is such that the strut and compound lifting mechanism cooperate in exactly the same way in all steering positions of the steering and lifting handle to elevate the platform at different speeds and under different mechanical advantages.

A still further feature of my invention resides in a very novel form of mechanism for urging the lifting member or strut secured to the elevating platform, into engagement with lifting

means operated by the steering and lifting handle, when the elevating platform is in its lowered position. Through this arrangement of the parts, immediately upon lowering of the elevating platform, the operator may begin the lifting operation without performing additional acts. This is a great convenience and advantage as will be appreciated by those skilled in the art.

10 A further feature of my invention resides in means for yieldingly moving the lifting member or strut away from the lifting means actuated by the steering and lifting handle, after the elevating platform is elevated to a predetermined position. Because of this arrangement of the parts, when the elevating platform is raised to a predetermined position and held there by holding mechanism, upward swinging movement of the steering and lifting handle will relieve the stress between the lifting means operated by the handle and the lifting member or strut of the elevating platform. The means urging the lifting member or strut away from engagement with the lifting means will then be effective to move the said lifting member away from engagement with the lifting means. This will of course contribute a free steering and lifting handle, all as is very desirable in the art.

15 A further important contribution of my invention resides in embodying in a single means the two features which I have just outlined. Thus, through utilization of a novel operating mechanism, preferably in the form of a spring pressed lever, the lifting member or strut of the elevating frame is urged towards the lifting means of the steering and lifting handle when the elevating platform is in its lowered position, and is urged away from the said lifting means when the elevating platform reaches a predetermined elevated position.

20 25 30 35 40 45 50 I have thus described generally the main features of my invention in order that a better understanding of the relation of my invention to the prior art may be had. There are of course additional valuable features inherent in my invention that I have not, up to this point, outlined, because those features will best be understood from the specific disclosure that follows. Naturally, I consider my contribution to the art to be of considerable breadth, and I shall solicit the grant of patent claims that will prevent the appropriation of my invention by those skilled in the art in forms varying mechanically from the particular form of my invention hereinafter set forth.

25 30 35 40 45 50 55 For a detailed description of my invention I shall refer to the drawings wherein Fig. 1 is an elevation of a truck to which my invention is

shown applied. Fig. 2 is a vertical partial section through the front end of the truck showing the elevating platform lowered. Fig. 3 is a view similar to Fig. 2 but illustrating the elevating platform in its fully elevated position. Fig. 4 is a view showing the parts of Fig. 2 in positions illustrating the manner in which a free lifting handle is obtained. Figs. 5, 6 and 7 are respectively figures taken along lines 5-5, 6-6 and 7-7 of Fig. 2.

I shall now refer more particularly to the drawings to describe the specific structure of the truck therein shown as embodying my invention. In describing the structure of the truck I shall refer to the parts by the specific means I have chosen for them, rather than by generic terms, but those skilled in the art will readily appreciate that the parts of my invention may be varied widely while operating to yield the action that is the contribution of my invention.

Referring first to Fig. 1, I show there a single frame truck comprising an elevating platform 10 and a lifting head designated generally by reference numeral 11, there being several reference numerals 11 applied to the lifting head in order to indicate better its outline. The forward end of the elevating platform 10 is formed with a vertical standard 12 as is best shown in Figs. 1, 2 and 3, the standard being welded to the elevating platform or otherwise secured as manufacturing technique may make desirable. The upper end of the standard 12, as best seen in Figs. 2 and 5, has bearings at 13 and 14 at each side thereof for mounting a pair of shafts 15. Pivotally supported on these shafts 15 are parallel links 16 that are welded or otherwise secured to a sleeve 17. The sleeve 17 is in turn mounted through suitable bushings about a shaft 18 supported in bearings 19 formed at the upper end of the lifting head 11.

The forward end of the elevating platform 10, immediately below the standard 12, supports a shaft 20 on bearings 21. On the shaft 20 are mounted opposed links 22 connected by a sleeve 20a. These links are supported for pivotal movement through sleeve 23a about shaft 23 mounted on the lower extension 24 of the lifting head. A pair of rods 25 are pivoted at 25a to the opposed links 22, the rods extending to the rear of the elevating platform where they are pivoted at 26 to links 27. The links 27 are in turn supported on shaft 28 carried by the elevating platform 10, and have mounted thereon rear lifting wheels 29. It is now obvious that as the forward end of the elevating platform 10 moves upwardly relatively to the lifting head about lower links 22 and upper links 16, the rear wheels 29 will be moved downwardly by rods 25 and links 27 to raise simultaneously the rear end of the elevating platform. The particular construction of the elevating platform and lifting head thus far described is not per se the invention to be claimed in this application, but is set forth here merely to illustrate one type of truck with which my invention may cooperate.

For maintaining the elevating platform in any elevated position to which it is moved, I utilize a hydraulic holding mechanism designated generally by reference numeral 30 in Figs. 2, 3 and 5. The cylinder of this hydraulic holding mechanism is pivoted on shaft 31 relatively to the lifting head, while its ram or piston is formed with a ball portion 32 fitting against a rounded surface 33a of a bracket 33 that is integral with the forward standard 12 of the elevating plat-

form. The piston of the hydraulic lifting mechanism is designated by reference numeral 34, and extends upwardly through the ball portion 32 and above the plate 35 of the standard 12, whereby to support for rotation relatively thereto a handle 36.

The handle 36 has secured thereto one end 37 of a spring 38, (Fig. 2) the other end being held fixed to the plate 35 by a stud 39. The handle 10 36 has also secured thereto the square end 40 of a valve stem 41 that is in threaded engagement at 42 with a block 43 fixed to the piston 34. Those skilled in the art will appreciate that the spring 38 holds the handle 36 in that position 15 in which the head 42 of the valve stem 41 prevents the flow of fluid as is required for a lowering of the platform. When it is desired to lower the platform from any elevated position, the handle 36 is rotated against the pressure 20 of spring 38 and rotates therewith the valve stem 41. The valve stem 41, because of its screw threaded engagement at 40a with the block 43 secured to piston 34, is moved downwardly to unseat the valve head 42. This of course allows 25 a flow of fluid past the valve head 42 so that the elevating platform may be lowered. The construction and operation of the hydraulic holding mechanism is herein illustrated because it is required in a truck of the class described. It 30 does not however form part of my invention herein claimed.

The bracket 33 secured to the elevating platform standard 12 extends forwardly and terminates at 50 in a vertical bearing 51 for a strut 35 support 52. Pivoted to the strut support 52 at 53 is a lifting member that I choose to call a lifting strut, here designated by reference numeral 54. A rod 55 extends through ear 56 formed on the strut, the said rod being utilized for moving the strut as is hereinafter set forth. Formed also as part of the strut 54 are a pair of ears 57 best shown in Fig. 7, between which extends the shaft 58. The function of the shaft 58 will be explained shortly.

45 The forward end of the lifting head 11 is adapted to support what is termed a steering head. As shown in the drawings, this steering head comprises a main casting 60 having a sleeve extension 61 which through a bushing 62 50 is mounted for rotation in the cylindrical extension 63 of the lifting head 11. Those skilled in the art will of course appreciate that the sleeve 61 through a bearing block 64 supports the forward steering wheels S in a manner well known 55 in the art. Formed as an integral part of block 64, and therefore rotatable with the steering head, is a foot support F. This foot support is useful to present a surface relatively to which the operator may brace himself when lifting the 60 load in all steering positions of the steering head.

The steering head casting 60 is formed with bearings for supporting the shaft 65 on which it is mounted for pivotal rotation the casting 66 forming part of the steering and lifting handle 65 assembly, designated by reference numeral 67.

The casting 66 carries a pair of lift pins 68 and 69 adapted to be applied sequentially to the surfaces 70 and 71 of the lifting strut 54. It will of course be appreciated that through the 70 pin 69 cooperating with surface 70 of the lifting strut 54 the steering and lifting handle assembly will elevate the platform 10 at a comparatively high speed. When the pin 69 contacts the surface 71 of the strut 54 during the latter part 75 of the elevating operation, as illustrated in Fig.

3, the lifting will be at a lower rate of speed but the mechanical advantage will of course be greater so that the lifting operation will be easier.

What I term a connecting or control lever, is designated by reference numeral 75, and is pivoted at 76 on the lifting head. A spring 77 is secured at 78 to the lifting head and at 79 to the lever 75, and tends to rotate the said lever in a counterclockwise direction about the shaft 76. The lever 75 extends upwardly at one side of its bearing on shaft 76 so as to lie between the ears 57 of the lifting strut 54 for cooperation with shaft 58. Surface 80 of the said lever 75 is adapted for cooperation with a surface 81 of the lifting strut, as will be made apparent presently.

When the elevating platform is in its lower position of Fig. 2, the spring 77 rotates the lever 75 so that the surface 80 thereof presses against the surface 81 of the strut 54 and brings the surface 70 of the said strut against lift pin 68. It may therefore be said that when the elevating platform is in its lowered position, it is the function of the lever 75 to maintain the strut 54 in lifting engagement with the lift pin 68. With the parts in the position of Fig. 2, the operator may place his foot against the rod 55 and move the strut clockwise about its pivot 53 and against the force of the spring 77 so as to release lift pin 68 from the strut surface 70. This will contribute a free handle in the event the operator does not wish to lift the platform, but merely wishes to move the truck.

With the parts in the position of Fig. 2, downward swinging movement of the handle assembly 67 acts first through the lift pin 68 and then through the lift pin 69 to bring the parts into the position of Fig. 3. In that figure, it will be noted that the surface 75a of the lever 75 is against the shaft 58 of the strut 54. It is obvious therefore, that the lever 75 is through the shaft 58 urging the strut 54 so as to bring its surface 71 away from engagement with lift pin 69. With the parts in the position of Fig. 3, should the steering and lifting handle assembly 67 be swung upwardly, the strut 54 will immediately move clockwise due to the relieving of the stress at 69, 71, and a free lifting handle will result. Of course, if thereafter the operator wishes to lower the elevating platform, he will operate the valve mechanism of the hydraulic holding mechanism through handle 36 as was already explained. The lowering of the elevating platform and the strut 54 therewith, will act to bring the strut 54 into that relation to the lever 75 that is illustrated in Fig. 2. This will effect the positioning of the strut 54 so that upward swinging movement of the steering and lifting handle assembly 67 will automatically bring lifting pin 68 into engagement with the surface 70. Thereafter, the lifting operation may readily be repeated.

In Fig. 4, there is illustrated in dash and dot lines the critical point at which the lever 75 ceases to function as a means for bringing the lifting strut 54 into engagement with the lift pin 68 and functions as a means tending to withdraw the strut from that engagement. Thus, it will be seen in dash and dot lines in Fig. 4, that the lifting strut 54 has moved so as to bring its surface 81 above the surface 80 of the lever 75. On the other hand, stub shaft 58 has been moved opposite the hump 75b of the lever 75 so that the said lever tends to rotate the strut 54 from its dash and dot line position to its full line position.

This the strut will do as soon as pressure is relieved between it and the lift pin 68.

With the elevating platform in the position of Fig. 4, and with the strut in its full line position in that figure, it is sometimes desirable to raise the elevating platform further. The operator then merely can actuate the rod 55 to move the strut into its dash and dot line position for engagement with lift pin 68. The downward 10 swinging movement of the steering and lifting handle assembly 67 will then effect the completion of the lifting operation of the platform.

I believe that the construction and mode of operation of my invention will now be fully understood.

I now claim:

1. In a truck of the class described, a lifting head, a steering head rotatable on said lifting head, an elevating platform, means mounting 20 said elevating platform for elevating movement relatively to said lifting head, a part of said elevating platform overhanging a part of said lifting head and extending into the axis of rotation of said steering head, a lifting strut pivoted on said overhanging part and extending downwardly toward said lifting head in said axis of rotation, a lifting lever pivoted on said lifting head for vertical swinging movement, thrust means on said lifting lever whereby said lifting lever applies lifting thrust to said lifting strut, and means 30 yieldingly moving said thrust means and lifting strut into engagement when said lifting lever is in a substantially vertical position, said strut being movable against the pressure of said yielding means to allow free downward swinging of said steering lever without lifting movement of said elevating platform.

2. In a truck of the class described, a lifting head, an elevating platform, means mounting 40 said elevating platform for elevating movement relatively to said lifting head, a part of said elevating platform overhanging a part of said lifting head, a lifting strut pivoted on said overhanging part and hanging downwardly on its pivot mounting toward said lifting head, a lifting lever pivoted on said lifting head for vertical swinging movement, thrust means movable with said lifting lever and separate from said strut for engaging a surface on said strut and for applying 45 lifting thrust thereto to elevate said elevating platform, and means yieldingly urging said strut for rotation on its pivot toward engagement with said thrust means when said elevating platform is in its lowered position.

3. In a truck of the class described, a lifting head, an elevating platform, means mounting 55 said elevating platform for elevating movement relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, thrust means movable with said lifting lever for engaging 60 said strut and for applying lifting thrust thereto to elevate said elevating platform, and means yieldingly urging said strut toward engagement with said thrust means when said elevating platform is in its lowered position and urging said strut away from said thrust means when said elevating platform is elevated above a predetermined position.

4. In a truck of the class described, a lifting head, an elevating platform, means mounting 70 said elevating platform for elevating movement

relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, thrust means movable with said lifting lever for engaging said strut and for applying lifting thrust thereto to elevate said elevating platform, and means yieldingly urging said strut toward engagement with said thrust means when said elevating platform is in its lowered position and urging said strut away from said thrust means when said elevating platform is elevated above a predetermined position, the thrust developed between said thrust means and said strut holding them in engagement until said thrust is relieved as at the end of the lifting stroke of the lifting lever.

5. In a truck of the class described, a lifting head, an elevating platform, means mounting said elevating platform for elevating movement relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, thrust means movable with said lifting lever for engaging said strut and for applying lifting thrust thereto to elevate said elevating platform, a pivoted lever spring pressed yieldingly for rotation about its pivot and relatively to said strut, a portion of said lever at one side of its pivot contacting said strut when said elevating platform is in its lowered position, and a portion of said lever at the other side of said pivot contacting the strut when said elevating platform is elevated.

6. In a truck of the class described, a lifting head, an elevating platform, means mounting said elevating platform for elevating movement relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, thrust means movable with said lifting lever for engaging said strut and for applying lifting thrust thereto to elevate said elevating platform, a lever pivoted on said lifting head and spring rotated relatively to said strut, a portion of said lever at one side of its pivot contacting said strut when said elevating platform is in its lowered position whereby to press said strut toward said thrust means, and a portion of said lever at the other side of said pivot contacting said strut when said elevating platform is raised whereby to press said strut away from said thrust means.

7. In a truck of the class described, a lifting head, an elevating platform, means mounting said elevating platform for elevating movement relatively to said lifting head, a part of said elevating platform overhanging a part of said lifting head, a lifting strut, a support for said lifting strut rotatable in a vertical axis on said overhanging part of the elevating platform, means pivotally mounting said strut on said support with said strut extending vertically downwardly toward said lifting head, a lifting lever pivoted on said lifting head for vertical swinging movement, and thrust means whereby said lifting lever applies lifting thrust to said lifting strut.

8. In a truck of the class described, a lifting head, an elevating platform, means mounting

said elevating platform for elevating movement relatively to said lifting head, a steering head rotatable on said lifting head, a part of said elevating platform overhanging a part of said lifting head, a lifting strut, a support for said strut rotatably mounted on said overhanging part of said elevating platform in the steering axis of said steering head, means pivotally mounting said strut on said support with said strut hanging downwardly substantially in the steering axis, a lifting and steering handle pivoted on said steering head for vertical swinging movement, and thrust means whereby said handle applies lifting thrust to said lifting strut.

15. 9. In a truck of the class described, a lifting head, an elevating platform, means mounting said elevating platform for elevating movement relatively to said lifting head, a steering head rotatable on said lifting head, a lifting strut mounted

20 on said elevating platform and depending downwardly therefrom toward said steering head substantially in the steering axis of said steering head, a steering and lifting handle pivoted on said lifting head for vertical swinging motion, a part secured on said steering and lifting handle for engaging said strut to impart vertical lift thereto and to said elevating platform, spring pressed means mounted for movement on said steering head and adapted to urge said strut toward engagement with handle part when said elevating platform is lowered, said spring pressed means urging said strut out of engagement with said handle surface when said elevating platform and strut are raised to a predetermined position.

35. 10. In a truck of the class described, a lifting head, an elevating platform, means mounting said elevating platform for elevating movement relatively to said lifting head, a steering head rotatable on said lifting head, a lifting strut mounted

40 for rotation on said elevating platform in the steering axis of said steering head and depending downwardly therefrom toward said steering head substantially in the steering axis of said steering head, a steering and lifting handle pivoted on said lifting head for vertical swinging motion, thrust means on said steering and lifting handle for engaging said strut to impart vertical lift thereto and to said elevating platform, said

45 strut being rotatable with said steering and lifting handle into all steering positions of said steering and lifting handle, spring pressed means mounted for movement on said steering head and adapted to urge said strut toward engagement with said handle thrust means when said elevating platform is lowered, said spring pressed means urging said strut out of engagement with said handle part when said elevating platform is raised to a predetermined position.

55. 11. In a truck of the class described, a lifting head, an elevating platform, means mounting said elevating platform for elevating movement relatively to said lifting head, a steering head rotatable on said lifting head, a lifting strut mounted

60 for rotation on said elevating platform in the steering axis of said steering head and depending downwardly therefrom toward said steering head substantially in the steering axis of said steering head, a steering and lifting handle pivoted on

65 said lifting head for vertical swinging motion, thrust means on said steering and lifting handle for engaging said strut to impart vertical lift thereto and to said elevating platform, means whereby said strut is rotatable with said steering and lifting handle into all steering positions of

said steering and lifting handle, spring pressed means mounted for movement on said steering head and adapted to urge said strut toward engagement with said handle thrust means when said elevating platform is lowered, said spring pressed means urging said strut out of engagement with said handle part when said elevating platform is raised to a predetermined position.

12. In a truck of the class described, a lifting head, an elevating platform, means mounting said elevating platform for elevating movement relatively to said lifting head, a steering head rotatable on said lifting head, a lifting strut, means mounting said strut for rotation on said elevating platform in the steering axis of said steering head and for pivotal movement on a horizontal axis, said strut hanging downwardly from its mounting means toward said steering head substantially in the steering axis of said steering head, a steering and lifting handle pivoted on said lifting head for vertical swinging motion, thrust means integral with said steering lever and separate from said strut whereby said steering and lifting handle engages a surface of said strut to impart vertical lift thereto and to said elevating platform, and said thrust means through said surface rotating said strut on its mounting means whereby to actuate said strut in all steering positions.

13. In a truck of the class described, a lifting head, an elevating platform, means mounting said elevating platform for elevating movement relatively to said lifting head, a lifting lever pivoted on said lifting head and adapted for vertical swinging movement, thrust means movable by said lifting lever, lift means secured to said elevating platform adapted to engage and to be actuated by said thrust means, and means yieldingly urging said lift means and thrust means into engagement when said elevating platform is in its lowered position, and urging said thrust means and lift means out of engagement when said elevating platform is elevated.

14. In a truck of the class described, a lifting head, an elevating platform, means mounting said elevating platform for elevating movement relatively to said lifting head, a lifting lever pivoted on said lifting head and adapted for vertical swinging movement, thrust means movable by said lifting lever, lift means secured to said elevating platform adapted to engage and to be actuated by said thrust means to lift said elevating platform, and means mounted on said lifting head yieldingly urging said thrust means and said lift means into engagement when said elevating platform is in its lowered position, and urging said thrust means and lift means out of engagement when said elevating platform is elevated.

15. In a truck of the class described, a lifting head, an elevating platform, means mounting said elevating platform for elevating movement relatively to said lifting head, a lifting lever pivoted on said lifting head and adapted for vertical swinging movement, thrust means movable by said lifting lever, lift means secured to said elevating platform adapted to engage and to be actuated by said thrust means to lift said elevating platform, a lever pivoted on said lifting head, a spring rotating said lever on its pivot and relatively to said lift means, one part of said lever contacting said lift means when said elevating platform is lowered whereby to urge said lift means toward said thrust means, and a second portion of said lever contacting said lift means when said elevating platform is raised whereby

to urge said lift means out of engagement with said thrust means.

16. In a truck of the class described, a lifting head, an elevating platform, means mounting said elevating platform for elevating movement relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, and a pair of pins carried by said lifting lever for engaging said strut sequentially whereby to impart thrust thereto as said lever swings vertically downwardly.

17. In a truck of the class described, a lifting head, an elevating platform, means mounting said elevating platform for elevating movement relatively to said lifting head, a part of said elevating platform overhanging a part of said lifting head, a lifting strut pivoted on said overhanging part and extending downwardly toward said lifting head, a lifting lever pivoted on said lifting head for vertical swinging movement, a pair of pins carried by said lifting lever for engaging said strut sequentially whereby to impart thrust thereto as said lever swings vertically downwardly, and spring pressed means yieldingly urging said strut against one of said pins when said elevating platform is in its lowered position, and away from said pins when said elevating platform is raised to a predetermined position.

18. In a truck of the class described, a lifting head, an elevating platform, means mounting said elevating platform for elevating movement relatively to said lifting head, a lifting lever pivoted on said lifting head and adapted for vertical swinging movement, lift imparting means movable by said lifting lever, lift means engaged by said lift imparting means for lifting said elevating platform, yielding means positioned relatively to said lift imparting means and lift means when said elevating platform is lowered whereby to urge said lift imparting means and lift means into engagement, and said yielding means being positioned relatively to said lift imparting means and lift means when said elevating platform is raised to urge said lift imparting means and lift means out of engagement.

19. In a truck of the class described, a lifting head, an elevating platform, means mounting said elevating platform for elevating movement relatively to said lifting head, a lifting lever pivoted on said lifting head and adapted for vertical swinging movement, lift imparting means connected to and movable by said lifting lever, lift means connected to and movable with said elevating platform and adapted for actuation by said lift imparting means for lifting said elevating platform, yielding means positioned relatively to said lift imparting means and lift means when said elevating platform is lowered whereby to urge said lift imparting means and lift means into engagement, and said yielding means being positioned relatively to said lift imparting means and lift means when said elevating platform is raised to urge said lift imparting means and lift means out of engagement.

20. In a truck of the class described, a lifting head, an elevating platform, means mounting said elevating platform for elevating movement relatively to said lifting head, a lifting lever pivoted on said lifting head and adapted for vertical swinging movement, lift imparting means movable by said lifting lever, lift means engaged

by said lift imparting means for lifting said elevating platform, yielding means adapted to urge said lift imparting means and lift means into engagement when said elevating platform is lowered, and to urge said lift imparting means and lift means out of engagement when said elevating platform is raised.

21. In a truck of the class described, a lifting head, an elevating platform, means mounting said elevating platform for elevating movement relatively to said lifting head, a lifting lever pivoted on said lifting head and adapted for vertical swinging movement, thrust means movable by said lifting lever, lift means secured to said elevating platform adapted to engage and to be actuated by said thrust means, yielding means positioned relatively to said lift means and thrust means when said elevating platform is lowered whereby to urge said lift means and thrust means

15

into engagement, and said yielding means being positioned relatively to said lift means and thrust means when said elevating platform is raised to urge said lift means and thrust means out of engagement.
